FIG. 9

UNITED STATES PATENT OFFICE.

ARTHUR J. BRIGGS, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,131,670.

Specification of Letters Patent. Patented Mar. 16, 1915.

Application filed August 22, 1913. Serial No. 786,107.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines, and more particularly to line spacing mechanism.

The main object of the invention, generally stated, is to provide line spacing mechanism which is simple in construction, inexpensive to manufacture and which is efficient in use.

To the above and other ends which will hereinafter appear, my invention consists in the features of construction, arrangements of parts and combinations of devices set forth in the following description and particularly pointed out in the claims.

In the accompanying drawings, Figure 1 is a fragmentary front elevation, with parts sectioned away, of the right-hand end of a carriage equipped with the line spacing mechanism of my invention. Fig. 2 is a plan view of the same with parts broken away. Fig. 3 is a detail fragmentary perspective view showing the line spacing pawl, a part of the hand lever, and some of the associated parts. Fig. 4 is a detail end view of the platen and some of the associated parts. Fig. 5 is an end view of the parts shown in Fig. 2 as the same are seen when looking in the direction of the arrow in Fig. 2.

As shown in the present instance, the carriage comprises a traverse or guide bar 1, to which is detachably fixed upwardly extending end plates or brackets 2, the right-hand bracket alone being shown in the drawings. These end plates 2 are connected by a tie-rod 3 and are apertured at 4 to form bearing openings for a platen shaft 5, the tie-rod 3 and platen shaft being parallel. A rotative platen 6 is carried by the platen shaft and has its right-hand platen head 7 formed with crown ratchet teeth 8 to constitute a line spacing wheel for the platen. The teeth 8 project to the right from the outer side or end of the platen head 7.

A roller detent 9 is adapted to bear against the teeth 8 of the line spacing wheel 55 to maintain the platen against accidental

displacement from the line space position to which it may be moved. This roller detent is mounted on a carrier which is designated as a whole by the reference numeral 10 and consists of a bracket arm 11 on which the roller detent is mounted and an integral bearing sleeve 12 which surrounds the tie-rod 3 and is adapted to move longitudinally thereon. The bracket arm 11 is extended forwardly at 13 where it is slotted, as at 14, to receive a pin 15 which projects inwardly from the right end plate 2 of the carriage. The pin and slot connection thus established between the member 10 and the right-hand end plate of the carriage enables the member 10 to receive a sliding movement along the tie-rod 3 but prevents said member from turning on the rod. A coiled expansion spring 16 surrounds the rod 3 and bears at one end against the right-hand end plate 2 of the carriage and at its opposite end against the sleeve 12. The force of this spring is therefore exerted to force the member 10 to the left and to force the detent roller 9 into engagement with the teeth of the line spacing wheel.

The line spacing devices for transmitting movement to the line spacing wheel consist in the main of two parts, one a line spacing pawl, designated as a whole by the reference numeral 17, and the other a sheet metal line spacing lever, designated as a whole by the reference numeral 18. As best shown in Fig. 3, the line spacing pawl comprises an engaging nose 19 which projects from a hub-like portion 20 connected to or formed as a part of a sleeve 21. This latter surrounds the platen shaft 5 and receives a bearing thereon for movement longitudinally of the shaft and also around the axis thereof. The sleeve 21 extends on opposite sides of the member 20 and forms trunnion-like projections. From an inspection of Fig. 1 it will be seen that the left-hand end portion of this sleeve is received in a chamber 22 formed in the right-hand platen head, whereas the right-hand end of the sleeve 21, in the normal position of the parts, abuts the inner face of the right-hand end plate 2 of the carriage. The pawl is thus supported and guided in its rotative movement around, and its sliding movement along, the platen shaft. A pin 23 projects from the pawl on the side thereof opposite the engaging nose 19, and is adapt-

ed to be received in a slot 24 formed in an arm 25 which projects from and forms part of the hand lever 18.

The hand lever 18 is preferably made of sheet metal and is provided with a hook-like finger piece 26 and with a yoke-like portion 27. The yoke-like end portion of the hand lever provides two parallel bearing arms 28 and 29. A shouldered pivot screw 30 extends through a bearing opening in the arm 28 and is received at its threaded end in a tapped opening in the right-hand end plate 2 of the carriage. The other parallel arm 29 of the lever is received in a horizontally disposed slot 31 formed in the end plate 2. A vertically disposed pivot pin 32 extends into an opening in the end plate 2 and passes through a bearing opening in the arm 29. The pivot pin 32 and shouldered screw 30 thus constitute a pivotal connection for the hand lever and afford a substantial support for the hand lever on the carriage, the points of pivotal connection of the two arms 28 and 29 being widely separated and the arm 29 being guided in the slot 31 in the end plate. A coiled spring 33 surrounds the shoulder screw 30 and is fixed at one end, as at 34, by being seated in an opening in the end plate 2. The opposite end 35 of the spring bears against a headed pin 36 which extends downwardly from the lower side of the forwardly projecting lever arm of the hand lever 18. The force of this spring is exerted to normally maintain the hand lever 18 in the position shown in Fig. 2; the lever being limited in its movement in this direction by the arm 25 abutting a wall 31^a of the slot 31, as shown in Fig. 2. The arm 29 of the hand lever is formed with a projecting stop 37 which limits the movement of the lever away from the normal position, when a double line space movement, indicated by the arrow *a* in Fig. 4, is being effected, the stop 37 will cooperate with the outer face of the right-hand end plate 2 of the carriage to limit the movement of the hand lever to the right, and thus determine the extent of line spacing movement to be given the platen.

I have made provision for single line spacing, indicated by the arrow *b* in Fig. 4, by providing a pivoted sheet metal stop member designated as a whole by the reference numeral 38. This stop member is pivoted on a shouldered pivot screw 39 to the end plate 2 of the carriage, and is formed with a finger piece 40 by which it may be readily turned on its pivot from the dotted 60 to the full line position represented in Fig. 5. A stop projection 41 extends to the right from the plane of the stop member and when the latter is in the dotted line position shown in Fig. 5, the stop portion 41 will be removed from the path of the stop or engag-

ing portion 37 on the hand lever, thus enabling the hand lever to receive its full extent of movement for double line spacing. When, however, the stop member 38 is moved to the full line position, the part 41⁷⁰ will be interposed in the path of the member 37, thereby limiting the movement of the hand lever so as to afford only a single line space feed of the platen. I have also provided the stop member 38 with a foot⁷⁵ piece or projection 42 which limits the forward movement of said member to operative position by co-operating with the traverse bar 1 of the carriage, as shown in full lines in Fig. 5.

In order to retain the member 38 in either of the two positions to which it may be moved, I have formed such member with a laterally extending projection 43 which, as shown in Fig. 2, is bent up from the sheet metal from which the member 38 is formed. This projection is adapted to engage above the contracted portion 44 of the right-hand end plate 2 when the parts are in the full line position represented in Fig. 90⁵, and is adapted to engage below the lower edge of said contracted portion of the end plate when the parts are in the dotted line position, thus holding the member 38 against accidental displacement from either of the two positions to which it may be adjusted. It will be understood that the sheet metal member 38 is sufficiently flexible to afford a slight lateral deflection of said member to enable the projection 43 to pass from one side to the other of the contracted portion 44 of the end plate.

An expansion spring 45 surrounds the right-hand end portion of the sleeve 21 and bears at one end against the right-hand end plate of the carriage, and at its opposite end against a circumferential shoulder 46 formed on the sleeve 21. The force of this spring is exerted to move the line spacing pawl to the left and into engagement with the line spacing wheel, by shifting the pawl along the platen shaft. The force of this spring, however, is resisted, in the normal position of the parts, by the power of the spring 33 which is sufficient to overcome the power of the spring 45. Thus the wall 47 of the slot 24 in the hand lever engages on one side of the pin 23 of the pawl. The opposite side of the pin, in the normal position of the parts, is engaged by a fixed stop or guide 110⁴⁸ which is in the nature of a sheet metal bracket secured to the right-hand end plate 2 by a screw 49. The engaging face 50 of this stop constitutes a cam face against which the pin 23 of the pawl is adapted to bear and against which it is forced by the crank arm 25 of the hand lever, under the power of the spring 33 exerted thereon. It will be understood that as the hand lever is moved to the right from the normal position¹²⁰ 130

shown in Fig. 2, the engaging face 47 of the slot 24 in the hand lever will assume a position which is more nearly parallel with the axis of the platen and will enable the pawl to slide along the platen shaft, under the force of its spring 45, and into engagement with the line spacing wheel. This sliding movement of the pawl takes place at the first portion of the movement of the hand lever from its normal position and is substantially a rectilinear movement. When, however, an engagement is effected between the line spacing pawl and the line spacing wheel a rotative movement of the pawl is effected by the further movement of the hand lever to the right. This rotative movement of the pawl is effected by a direct action thereon of the hand lever through the pin and slot connection 23-24 between the two. In the return movement of the parts the engaging wall 47 of the slot 24 in the hand lever forces the pin 23 back into engagement with the cam face 50 of the stop and guide 48 and causes the pawl to be moved along the platen shaft to the normal position, it having been hereinbefore explained that the power of the spring 33 is sufficient to overcome that of the spring 45. From the foregoing description it will be understood that while the movement of the pawl along the platen shaft into engagement with the line spacing wheel is actually effected by the spring 45, nevertheless this movement of the pawl is controlled by the hand lever.

It will be seen that the hand lever swings horizontally and in its movement from normal to operative position the finger piece of the hand lever moves from left to right. It will be understood, therefore, that pressure exerted by the operator from left to right on the finger piece 26 is effective to produce a line spacing movement of the platen and is also effective to move the carriage from left to right to begin a new line of writing.

It will also be seen that the line spacing pawl is in fact a lever of the first order controlled directly by the hand lever, which is likewise a lever of the first order; that one arm 25 of the hand lever 18 bears directly on an arm 23 of the lever 17 and controls this last mentioned lever for movement along the platen shaft as well as for rotative movement around the axis thereof; and that the walls of the slot 24 in the hand lever are at times so disposed that they constitute cam faces operative on the pin 23 to control the movement of the pawl longitudinally of the platen and that the operation of the pawl is accurately and positively controlled.

In the present construction the line spacing pawl and the crank arm 25 of the hand lever are so constructed and arranged that they do not extend beyond the surface of the platen, so that the work sheet may overlap

and extend around the line spacing wheel if necessary, and in fact may surround the line spacing pawl and the devices by which it is actuated up to the right-hand end plate of the carriage. This is a matter of some importance in that it enables a wider sheet to be employed, without interference from the line spacing devices, than is ordinarily the case for a given length of platen.

It will be understood that the line spacing devices which coöperate with the line spacing wheel and by which a variation in the line spacing movements may be controlled, may be said to comprise in the main three parts, *i. e.*, the member 17, the hand actuated line spacing lever 18 and the member 38; that the parts 18 and 38 are made of sheet metal and are simple in form, and that the parts may be readily assembled and are not liable to be deranged or broken. It will be observed, therefore, that by the present invention I have provided line spacing devices which are simple in construction, inexpensive to manufacture, embodying but few parts and most of them made of sheet metal, and that the devices are efficient and reliable in use.

While from certain aspects of my invention the part 19 in itself may be regarded as a line spacing pawl, and the part 20-21-23 may be regarded as a carrier therefor, so that the rigidly united parts 19, 20-21-23 may be considered as a combined pawl and carrier, nevertheless from certain other aspects of the invention the parts 19, 20-21-23 all preferably formed from a single piece, may be regarded as the line spacing pawl designated as a whole by the reference numeral 17.

When I refer herein to a "combined pawl and carrier" I mean that the pawl and the carrier by which it is pivotally supported and carried are rigidly united, or are in effect one part and always move together.

Various changes may be made within the spirit and scope of the invention.

What I claim as new and desire to secure by Letters Patent, is:—

1. In a typewriting machine, the combination of a carriage, a rotative platen, a line spacing wheel, a combined rigidly united pawl and carrier mounted for rotative movement and for bodily axial movement longitudinally of the platen, and a hand lever operative to control the movement of the combined pawl and carrier axially into engagement with the line spacing wheel and to rotate the combined pawl and carrier after such engagement has been effected, the rotative movement of the combined pawl and carrier being effected directly by said hand lever.

2. In a typewriting machine, the combination of a carriage, a rotative platen, a line spacing wheel, a combined rigidly united

1. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, and a hand lever co-operative with said combined pawl and carrier to control the movement thereof longitudinally of the platen shaft and to effect the movement of said pawl and carrier around said shaft.
2. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, said combined pawl and carrier being in the nature of a lever of the first order, and a hand lever co-operative with one arm of the lever-like combined pawl and carrier.
3. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, said combined pawl and carrier being in the nature of a lever of the first order, and a hand lever co-operative with one arm of the lever-like combined pawl and carrier.
4. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, a hand lever co-operative with said combined pawl and carrier to control its movement longitudinally of the platen shaft and around the axis of said shaft, and a spring co-operative with said combined pawl and carrier and which moves the same into engagement with the line spacing wheel.
5. In a typewriting machine, the combination of a carriage, a rotative platen, a line spacing wheel, a combined pawl and carrier mounted on the platen shaft for movement around the axis thereof and for movement longitudinally of the shaft into and out of engagement with the line spacing wheel, a hand lever co-operative with said combined pawl and carrier to control its movement longitudinally of the platen shaft and around the axis of said shaft, a spring co-operative directly with said combined pawl and carrier and which tends to force it toward the line spacing wheel, and a means for arresting the combined pawl and carrier in its return to normal position.
6. In a typewriting machine, the combination of a carriage, a rotative platen, a line spacing wheel, a combined pawl and carrier mounted on the platen shaft for movement around the axis thereof and for movement longitudinally of the shaft into and out of engagement with the line spacing wheel, said combined pawl and carrier being in the nature of a lever of the first order, and a hand lever connected by a pin and slot connection with one arm of the lever-like combined pawl and carrier to control its movement longitudinally of the platen shaft and around the axis thereof.
7. In a typewriting machine, the combination of a carriage, a rotative platen, a line spacing wheel, a combined rigidly united pawl and carrier mounted for movement longitudinally on and around the platen shaft, and a hand lever pivoted to swing horizontally and operative to actuate said combined pawl and carrier to control its movement axially and rotatively and to return the carriage to begin a line of writing.
8. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, and a hand lever pivoted to swing horizontally and connected directly to said combined pawl and carrier to control its movement longitudinally of the platen shaft and to effect a movement of the combined pawl and carrier around the shaft and operative to return the carriage to begin a line of writing.
9. In a typewriting machine, the combination of a carriage, a rotative platen, a line spacing wheel, a combined rigidly united pawl and carrier mounted on the platen shaft for movement longitudinally of and around the axis of the platen, a hand lever operative on the pawl and carrier to control its movement axially into engagement with the line spacing wheel and to rotate the combined pawl and carrier after such engagement has been effected, and variable means for arresting the movement of said hand lever away from normal position, thereby determining the extent of line spacing movement that may be given the platen.
10. In a typewriting machine, the combination of a carriage, a rotative platen, a line spacing wheel, a combined rigidly united pawl and carrier mounted on the platen shaft for movement around the axis thereof and for movement longitudinally of the shaft into and out of engagement with the line spacing wheel, a hand lever co-operative with said combined pawl and carrier to control its movement longitudinally of the platen shaft and around the axis thereof, spring means for returning the hand lever and the combined pawl and carrier to normal position, and means for variably arresting the hand lever in its movement to operative position, thereby determining the extent of line feed movement that may be given the platen.
11. In a typewriting machine, the combination of a carriage, a rotative platen, a line spacing wheel, a combined pawl and carrier mounted on the platen shaft for movement around the axis thereof and for

movement longitudinally of the shaft into and out of engagement with the line spacing wheel, a hand lever coöperative with said combined pawl and carrier to control 5 its movement longitudinally of the platen shaft and around the axis thereof, a part of said hand lever forming a stop which co-operates with the carriage to limit the movement of the hand lever away from the normal 10 position, and a pivoted stop that may be moved into and out of the path of the stop on the hand lever to vary the extent of movement that may be given said lever and thus determine the extent of line spacing 15 movement that may be given the platen.

12. In a typewriting machine, the combination of a carriage, a rotative platen, a line spacing wheel carried thereby, a hand lever pivoted on the carriage to swing horizontally 20 and provided with a slot therein, and a combined line spacing pawl and carrier mounted on the platen shaft to move longitudinally thereon and to turn around the axis thereof and having a part that is received 25 in said slot in the hand lever to operatively connect the combined pawl and carrier with said lever.

13. In a typewriting machine, the combination of a carriage, a rotative platen, a line spacing wheel carried thereby, a hand lever pivoted on the carriage to swing horizontally 30 and provided with a slot therein, and a combined line spacing pawl and carrier mounted on the platen shaft to move longitudinally thereon and to turn around the axis thereof and having a part that is received 35 in said slot in the hand lever to operatively connect the combined pawl and carrier with said lever, the hand lever being normally disposed so that a wall of the slot 40 therein constitutes an inclined face which affords a movement of the combined pawl and carrier longitudinally of the platen shaft at the first part of the movement of the hand lever, to effect a connection between the pawl and line spacing wheel.

14. In a typewriting machine, the combination of a carriage, a rotative platen, a line spacing wheel carried thereby, a hand lever pivoted on the carriage to swing horizontally 50 and provided with a slot therein, a combined line spacing pawl and carrier mounted on the platen shaft to move longitudinally thereon and to turn around the axis thereof and having a part that is received 55 in said slot in the hand lever to operatively connect the combined pawl and carrier with said lever, spring means for returning the hand lever and the combined pawl and carrier to normal position, a stop 60 formed as a part of the hand lever, a stop which co-operates therewith to limit the movement of the hand lever from normal position, and means which co-act with the

combined pawl and carrier to limit its return movement to normal position. 65

15. In a typewriting machine, the combination of a carriage, a rotative platen, a line spacing wheel carried thereby, a hand lever pivoted on the carriage to swing horizontally 70 and provided with a slot therein, a combined line spacing pawl and carrier mounted on the platen shaft to move longitudinally thereon and to turn around the axis thereof and having a part that is received in said slot in the hand lever to operatively connect the combined pawl and carrier with said lever, the hand lever being normally disposed so that a wall of the slot therein constitutes an inclined face which affords a 75 movement of the combined pawl and carrier longitudinally of the platen shaft at the first part of the movement of the hand lever, in order to effect a connection between the pawl and line spacing wheel, a spring 80 which tends to force the combined pawl and carrier along the platen shaft and toward the line spacing wheel, and a spring for returning the hand lever to normal 85 position. 90

16. In a typewriting machine, the combination of a carriage, a rotative platen, a line spacing wheel carried thereby, a hand lever pivoted on the carriage to swing horizontally 95 and provided with a slot therein, a combined line spacing pawl and carrier mounted on the platen shaft to move longitudinally thereon and to turn around the axis thereof and having a part that is received in said slot in the hand lever to operatively connect the combined pawl and carrier with said lever, the hand lever being normally disposed so that a wall of the slot therein constitutes an inclined face which affords a 100 movement of the combined pawl and carrier longitudinally of the platen shaft at the first part of the movement of the hand lever in order to effect a connection between the pawl and line spacing wheel, a spring which tends to force the combined pawl and carrier 105 along the platen shaft and toward the line spacing wheel, a spring for returning the hand lever to normal position, stop means for limiting the movement of the hand lever away from normal position, and stop means 110 for limiting the return movement of the combined pawl and carrier to normal position. 115

17. In a typewriting machine, the combination of a carriage, a rotative platen, a line spacing wheel carried thereby, a hand lever pivoted on the carriage to swing horizontally 120 and provided with a slot therein, a combined line spacing pawl and carrier mounted on the platen shaft to move longitudinally thereon and to turn around the axis thereof and having a part that is received in said slot in the hand lever to op- 125

- eratively connect the combined pawl and carrier with said lever, the hand lever being normally disposed so that a wall of the slot therein constitutes an inclined face which 5 affords a movement of the combined pawl and carrier longitudinally of the platen shaft at the first part of the movement of the hand lever, in order to effect a connection between the pawl and line spacing wheel, a 10 spring which tends to move the combined pawl and carrier along the platen shaft and into engagement with the line spacing wheel, a spring for returning the hand lever to normal position, stop means for limiting the 15 movement of the hand lever away from normal position, said stop means comprising a pivoted member adapted to be moved into and out of the path of a part of said hand lever to variably arrest the latter and thus 20 determine the extent of line spacing movement to be given the platen, and stop means for limiting the return movement of the combined pawl and carrier to normal position.
- 25 18. In a typewriting machine, the combination of a carriage; a rotative platen; and line spacing means which do not extend beyond the surface of the platen and around which the work sheet on the platen may extend, said line spacing means comprising a line spacing wheel having teeth on the outer end or side thereof, a combined rigidly united line spacing pawl and carrier movable around the axis of the platen and also 30 movable bodily longitudinally of the axis of the platen, an actuating handle, and connecting means between said actuating handle and said combined pawl and carrier.
19. In a typewriting machine, the combination of a carriage; a rotative platen; and line spacing means which do not extend beyond the surface of the platen and around which the work sheet on the platen may extend, said line spacing means comprising a 35 line spacing wheel having teeth on the outer end or side thereof, a combined rigidly united line spacing pawl and carrier mounted on the platen shaft for movement around the same and also for bodily movement longitudinally of said shaft, and a lever actuated crank arm for controlling the movement of said combined pawl and carrier longitudinally of the platen shaft and for rotating it.
- 40 20. In a typewriting machine, the combination of a carriage; a rotative platen; and line spacing means which do not extend beyond the surface of the platen and around which the work sheet on the platen may extend, said line spacing means comprising a 45 line spacing wheel having teeth on the outer end or side thereof, a combined rigidly united line spacing pawl and carrier mounted on the platen shaft for movement around the same and also for bodily movement longitudinally of said shaft, and a lever actuated crank arm for controlling the movement of said combined pawl and carrier longitudinally of the platen shaft and for rotating it.
- 50 21. In a typewriting machine, the combination of a carriage; a rotative platen; and line spacing means which do not extend beyond the surface of the platen and around which the work sheet on the platen may extend, said line spacing means comprising a 55 line spacing wheel having teeth on the outer end or side thereof, a combined line spacing pawl and carrier mounted on the platen shaft for movement around and longitudinally of said shaft, and a lever actuated crank arm for controlling the movement of said combined pawl and carrier longitudinally of the platen shaft and for rotating it, said crank arm extending from its support toward an end of the platen and in the general direction of the length of the platen and making direct connection with the combined pawl and carrier.
- 60 22. In a typewriting machine, the combination of a platen; a line spacing wheel; and line spacing means for said wheel, said line spacing means comprising a line spacing pawl, a spring which moves said pawl into engagement with said line spacing wheel, a hand lever which co-acts with said pawl to control the movement thereof, and a spring for returning said hand lever to normal position and the force of which flexes and overcomes the force of said first mentioned spring.
- 65 23. In a typewriting machine, the combination of a rotative platen; a line spacing wheel; and line spacing means for said wheel, said line spacing means comprising a line spacing pawl mounted for movement longitudinally of the axis of the platen into and out of engagement with said line spacing wheel and also for rotative movement around the axis of the platen, a spring which moves said pawl into engagement with said line spacing wheel, a hand lever which co-acts with said pawl to control the movement thereof, and a spring for returning said hand lever to normal position and the force of which flexes and overcomes the force of said first mentioned spring.
- 70 24. In a typewriting machine, the combination of a rotative platen; a line spacing wheel; and line spacing means for said wheel, said line spacing means comprising a line spacing pawl normally disengaged from

- the line spacing wheel and mounted for movement longitudinally of the axis of the platen into and out of engagement with said line spacing wheel and also for rotative movement around the axis of the platen, a spring which moves said pawl longitudinally of the platen and into engagement with the line spacing wheel, and a hand lever which co-acts with said pawl to rotate it around the axis of the platen. 5
25. In a typewriting machine, the combination of a rotative platen; a line spacing wheel; and line spacing means for said wheel, said line spacing means comprising a line spacing pawl normally disengaged from the line spacing wheel and mounted for movement longitudinally of the axis of the platen into and out of engagement with said line spacing wheel and also for rotative movement around the axis of the platen, a spring which moves said pawl longitudinally of the platen and into engagement with the line spacing wheel, a hand lever which co-acts with said pawl to rotate it 10 around the axis of the platen, and a fixed stop with which said pawl co-acts to limit the return movement of the pawl. 20
26. In a typewriting machine, the combination of a rotative platen; a line spacing wheel; and line spacing means for said wheel, said line spacing means comprising a line spacing pawl normally disengaged from the line spacing wheel and mounted for movement longitudinally of the axis of the platen into and out of engagement with said line spacing wheel and also for rotative movement around the axis of the platen, a spring which moves said pawl longitudinally of the platen and into engagement with the line spacing wheel, and a spring restored hand lever which co-acts directly with said pawl to control the movement thereof into engagement with the line spacing wheel and to effect a rotative movement of said pawl around the axis of the platen. 25
27. In a typewriting machine, the combination of a rotative platen; a line spacing wheel; and line spacing means for said wheel, said line spacing means comprising a line spacing pawl mounted for movement longitudinally of the axis of the platen into and out of engagement with said line spacing wheel and also for rotative movement around the axis of the platen, a spring which moves said pawl longitudinally of the platen and into engagement with the line spacing wheel, a hand lever which co-acts directly with said pawl to control the movement thereof into engagement with the line spacing wheel and to effect rotative movement of said pawl around the axis of the platen, a spring for returning said hand lever to normal position and the force of which over- 30
- comes the force of and flexes said first mentioned spring, and a fixed stop and guide which co-acts with said pawl and limits its return movement to normal position. 65
28. In a typewriting machine, the combination of a rotative platen; a line spacing wheel; and line spacing means for said wheel, said line spacing means comprising a line spacing pawl mounted for movement longitudinally of the axis of the platen into and out of engagement with said line spacing wheel and also for rotative movement around the axis of the platen, a hand-lever which co-acts directly with said pawl, and a fixed cam with which the pawl directly co-acts and which guides the pawl and acts as a stop therefor in the return movement of the pawl to normal position. 70
29. In a typewriting machine, the combination of a rotative platen; a line spacing wheel; and line spacing means comprising a single member having a line spacing pawl rigidly connected therewith and normally disengaged from the line spacing wheel, said member being mounted for rotative movement and also for movement to throw the pawl into and out of engagement with the line spacing wheel, and a hand lever separate from said member but operative directly thereon for controlling such movements thereof. 75
30. In a typewriting machine, the combination of a rotative platen; a line spacing wheel; and line spacing means comprising a line spacing pawl mounted for rotative movement and for a distinct movement into and out of engagement with the line spacing wheel, and a hand lever separate from but operative directly on said pawl for controlling such movements thereof, said hand lever being formed with a yoke where it is pivotally supported and the pawl being supported independently of said hand lever. 80
31. In a typewriting machine, the combination of a rotative platen; a line spacing wheel; and line spacing means comprising a line spacing pawl, and a sheet metal hand lever separate from but operative directly on said pawl, said hand lever being formed with a yoke by which the lever is pivotally supported and said pawl being supported independently of said hand lever. 85
32. In a typewriting machine, the combination of a rotative platen; a line spacing wheel; and line spacing means comprising a single member having a line spacing pawl rigidly connected therewith, said member being mounted for rotative movement around the axis of the platen and also for movement longitudinally of the axis of the platen, and a hand lever separate from but directly operative on said member for controlling said movements thereof. 90
33. In a typewriting machine, the combi- 95

nation of a rotative platen; a line spacing wheel; and line spacing means comprising a line spacing pawl mounted for rotative movement and also for bodily movement 5 longitudinally of the axis of the platen, a hand lever for controlling said movements of the pawl, and a pin and slot connection between said pawl and lever.

34. In line spacing mechanism of a typewriter 10 writing machine including a cylindrical platen, line spacing wheel and platen shaft, the combination of a line spacing lever, and a spring-pressed pawl operative by said lever to turn the line spacing wheel, and 15 comprising a wheel-engaging nose and a hub fast together, the hub surrounding the platen shaft and being movable thereon axially by the spring, and both angularly and axially by the lever.
35. In line-spacing mechanism of a typewriter 20 including a cylindrical platen, line-spacing wheel and platen shaft, the combination of a spring-pressed line-spacing lever, and a spring-pressed pawl operative by said lever to turn the line-spacing wheel, and comprising a wheel-engaging nose and a hub fast together, the hub surrounding the platen shaft and being movable axially thereon in opposite directions 25
- 30 by said springs, and angularly thereon by said lever, the lever-spring acting through the lever on the pawl.
36. In a typewriting machine, the combination of a carriage including as a part of 35 its structure a tie rod; a rotative platen; a line spacing wheel; a detent which co-acts

with the teeth of the line spacing wheel; a carrier for said detent, said carrier being in the nature of a sleeve which surrounds and slides along said tie rod and carries the detent toward and away from the teeth of the line spacing wheel; and a coiled expansion spring which surrounds said rod and bears against said sliding carrier to force the detent against the teeth of the line spacing 45 wheel.

37. In a typewriting machine, the combination of a rotative platen; a carriage therefor including as a part of its structure a tie rod which extends longitudinally of the 50 platen and intermediate the ends thereof; a line spacing wheel having teeth which project from the outer side or end thereof; a roller detent which co-acts with the teeth of the line spacing wheel; a carrier for said 55 roller detent, said carrier being in the nature of a sleeve which surrounds and slides along said tie rod and which has an arm that supports the roller detent for movement toward and away from the teeth 60 of the line spacing wheel, and a coiled expansion spring which surrounds said rod and bears against said sliding carrier to force the detent against the teeth of the line spacing wheel.

Signed at Syracuse, in the county of Onondaga, and State of New York, this 20th day of August, A. D. 1913.

ARTHUR J. BRIGGS.
